APPARATUS FOR FACILITATING THE ADJUSTMENT OF VALVE STEMS OF INTERNAL COMBUSTION ENGINE FOR TAPPET CLEARANCE

Evan Meirion Arthur, West Heath, Birmingham, England

Application January 5, 1954, Serial No. 402,315

1 Claim. (Cl. 33—181)

This invention relates to means for facilitating the grinding in of valves and consequent required adjustment of the valve stem for tappet clearance in connection with valves of the kind in which adjustment means are not provided. Valves in such an arrangement have the valve head at one end of the valve stem and an enlarged head at the other end which is engaged by the tappet, and when such a valve is to be ground in, the valve assembly has to be taken down, and considerable labour is required in testing the adjustment for tappet clearance, and this invention has for its object improved and simplified construction of jig which facilitates the adjustment for tappet clearance.

Referring to the drawings:

Figure 1 is a perspective view of a device constructed according to this invention.

Figure 2 is an end view.

Figure 3 is a section on line 3—3 of Figure 1.

Figure 4 is a side elevation of a half guide sleeve on a valve stem, and

Figure 5 is a side elevation of a valve stem guide.

According to a convenient embodiment of this invention, the guide for the valve stem is detachably mounted on the valve stem and comprises a sleeve 1 having a screw threaded extension 2 at one end, the other end forming a cylindrical surface 3 for engaging the guide recess in the cylinder block. The sleeve is divided diametrically thereacross into two halves 4 and such halves are fixed together by means of a screwed ring 5 which engages the said screwed end of the assembled two halves of the sleeve, the ring being of a size to pass over the enlarged tappet end of the valve stem. The said cylindrical surface for engaging the guide recess is divided by a groove and a radial pin is provided on the sleeve to form a stop engaging the upper end of the recess, the valve spindle with the guide thereon being inserted from above. When the valve has been ground in, the valve is removed and the tappet end is filed or ground down to adjust for correct tappet clearance, and to ensure a ready means for testing correct adjustment, a jig is provided. Such jig comprises an abutment 6 against which the valve head 7 bears and a cradle for receiving the valve stem. An adjustable screwed pin 8 is mounted co-axially or in alignment with the valve stem thus arranged and the screwed pin is set against the tappet end 9 of the valve stem so that tests can be made during the process of the grinding or filing adjustment from such end 9. For instance, if after the valve has been ground in there is a tappet clearance of

2

.005 inch, .007 inch will have to be removed if the correct tappet clearance is .012 inch, and the jig enables this to be done and tested by a feeler gauge without having to assemble the valve on the engine to make tests to obtain correct adjustment. The jig comprises a base frame formed of two L-shaped sheet metal members 10 which are spot welded together to form a foot support 11 and two upstanding sheet metal webs 12 from which end lugs 13 project upwardly from each of the webs 12 of the members 10, the abutting backs of the members 10 forming the central plane of the appliance. Opposed semi-cylindrical walls 13a are shaped in each lug 13 of each pair and each hole thus formed is screw threaded for receiving a screwed pin. One screwed pin forms the abutment 6 and the other pin 8 forms an adjustable stop for contacting the end 9 on the valve stem 15. The lugs 13 are not fixed together and are adapted to spring grip the screwed pins to hold them in their adjusted position, whereby a very accurate setting can be made which will not be disturbed. Inclined lugs 17 also upstand from the webs 12 to form two V-shaped cradles on which the valve stem rests. Correct clearance adjustment is obtained by means of a feeler gauge between the end of the screw pin and the end of the valve stem 20 fitted in the jig. The valve stem can be spun on the cradles to test for straightness.

The final adjustment can be readily checked in position on the engine as the valve with the guide thereon can be quickly placed in position for testing.

Having thus described the invention, what is claimed as new and desired to be secured by Letters Patent, is:

An appliance for facilitating the adjustment of a valve stem for tappet clearance, comprising a base frame formed of two L-shaped sheet metal members placed back to back to form a foot support and two upstanding sheet metal webs, the abutting backs of such sheet metal members forming the central plane of the appliance, upstanding lugs at each end of the webs which each have a semi-cylindrical wall which are opposed and the hole thus formed screw threaded, a screwed adjusting pin which engages each said screw threaded hole, the walls of which spring press on the screwed pin to spring grip the pin and hold it tight in any position to which it is adjusted, opposed outwardly inclined lugs on the webs to form 35 V-shaped cradles for a valve stem, each screw pin forming respectively an abutment head on one side of the base frame against which the valve head on the stem is adapted to contact when supported by the V-shaped cradles and an adjustable abutment at the other side of the 40 base frame for contacting the tappet end of the valve stem and to test, by a feeler gauge, the amount removed from the stem.
